UNITED STATES PATENT OFFICE.

SAMUEL P. ERWIN, OF SANTA ROSA, CALIFORNIA.

ELEVATOR.

Application filed June 1, 1921. Serial No. 474,092.

To all whom it may concern:

Be it known that I, SAMUEL P. ERWIN, a citizen of the United States, residing at Santa Rosa, in the county of Sonoma and State of California, have invented certain new and useful Improvements in Elevators, of which the following is a specification.

This invention appertains to improvements in elevators, and more particularly to a type of the same adapted for use in stores, warehouses and the like, whereby to facilitate the handling of certain classes of merchandise therein.

The principal object of the invention is to provide for an elevating mechanism of the character mentioned, and one particularly adapted for facilitating the handling of loose materials in sacks and the like, and for the elevating of an open sack and effecting the discharge of the contents of the same into bins or receptacles located at a distance above the floor level of the store room or building.

Another object of the invention is to provide for an elevating apparatus or hoisting device of the class referred to, and one embodying a novel means whereby the same is retained in its positions of operation against accidental displacement or movement, but may be readily, easily and quickly manipulated for the movement thereof from one operative position to another.

With the foregoing and other objects in view, the preferred embodiment of the invention resides in the certain novel and useful construction and arrangement of parts as will be hereinafter more fully described, set forth in the appended claims, and illustrated in the accompanying drawing, in which:

Figure 1 is a vertical longitudinal section thereof showing the carriage in dumping position,

Fig. 2 is a front elevation of the same showing the carriage in its lowered position,

Fig. 3 is a transverse section taken on the line 3—3 of Fig. 1,

Fig. 4 is an enlarged fragmentary front elevation of the lower portion of one of the rails and of the hoisting carriage associated therewith,

Fig. 5 is an enlarged fragmentary side elevation of the portion as shown in Fig. 4, and,

Fig. 6 is a transverse section taken on the line 6—6 of Fig. 5.

Referring to the drawing, wherein similar characters of reference designate corresponding parts in the several views thereof, the numerals 10 and 11 indicate a pair of rails or trackways, formed of channelled iron or timber as desired, with the open sides thereof opposed one to the other, and held in spaced parallel relation by means of end cross bars 12 and 13.

Slidably mounted between the rails 12 and 13 is a carriage, preferably in the form of an open frame consisting of a pair of oppositely disposed frame members or pipe sections 14 and 15 lying parallel to the rails 10 and 11 and a pair of transversely extending frame members or pipe sections 16 and 17, the opposite ends of the lower section 16 being coupled to the lower ends of the sections 14 and 15 by means of four-way couplings 18, while the opposite ends of the upper section 17 are coupled to the upper ends of the sections 14 and 15 by means of a pair of four-way couplings 19. Extending outwardly of the couplings 18 and the couplings 19, in alignment with the opposite ends of the transverse frame members or pipe sections 16 and 17, are short stub members or spindles 20 upon which are revolubly mounted the rollers 21, which are arranged in rolling engagement with the lower side wall of the channels of the rails 10 and 11. Extending forwardly of the couplings 19 are the opposite leg portions 22 of a substantially U-shaped frame member which has its connected portion 23 upwardly and angularly inclined from points 24 medially of the length of the leg portions 22, with the transversely extending connected portion of the same lying in a plane slightly above that of the top faces of the rails 10 and 11. Depending from the couplings 18 in line with the vertical frame members or pipe sections 14 and 15, are a pair of leg members or pipe sections 24 and 25 having their lower end portions 24' and 25' slightly and angularly bent in an inward direction to lie in a vertical plane with respect to the rearward inclination of the carriage and its supporting rails, these angularly bent end portions are bifurcated to have journaled in each a roller 26.

Mounted for pivotal or tilting movement on the transversely extending connected portion 23 of the U-shaped member of the carriage, by means of a pair of spaced bearings or brackets 27 secured in position on the un-

der face of the bottom wall thereof, is an article or material carrying support or carrier 28 which is normally disposed in an upwardly and inwardly inclined position with its upper end portion disposed between the rails 10 and 11, and journaled at the opposite sides of the bottom wall of this upper end of the same, are a pair of rollers 29 arranged in rolling engagement with the channels of the rails 10 and 11.

For elevating and lowering the carriage on the rails 10 and 11, one end of a flexible element or cable 30 is secured, as at 31, to the lower transversely extending frame member or pipe section 16, and extends therefrom upwardly of and medially between the rails 10 and 11, and is trained over a roller 32, bracketed as at 33, on the lower face of the upper cross bar 13, and from thence downwardly to a winding roller 34 which is journaled transversely of the rails and on the lower faces thereof at a point inwardly of the lower ends of the same. The shaft 35, of the roller 34, has one end projecting outwardly of the rail 11 to receive thereon a ratchet wheel 36, and a hand crank 37, a pawl 38 being pivoted on the outer side face of the rail 15 for cooperation with the ratchet wheel 36, whereby to hold the carriage in any desired position on the rails 10 and 11.

At the upper ends of the rails 10 and 11, there is provided a pair of upwardly and inwardly curved guide members 39, and the same are bolted in position on the inner faces of the outer side walls of the rails 10 and 11, and in alignment with the upper flanges or walls of the channels thereof, suitable portions of the latter being cut away to permit of such desired arrangement. It is to be noted, that the thickness of the guide members 39 is slightly greater than that of the upper wall or flange of the channels of the rails 10 and 11, and that the upper faces of the members 39 are arranged flush with the upper faces thereof, so that the lower faces of these members project below the lower faces of the same, and that the connected ends of the members lie in the path of the rollers 21 of the carriage, and prevent the same from leaving the rail channel, when the carriage is hoisted to the upper end of the rails.

In the use of the elevator, which has been designed primarily for the hoisting of opened sacks or any other article or merchandise handled in the store, warehouse or on the farm and the dumping of the contents of the same into bins or receptacles, such as are indicated as at *a*, a sack *b* is placed within the support or carrier 28, on the carriage, when the latter is in its lowered position, and with its open end upwardly thereof, when upon the turning of the crank handle 37, the cable 30 will be wound onto

the winding roller 34, and the carriage elevated to the upper ends of the rails 10 and 11. At the end of the upward movement of the carriage, the rollers 29, of the support or carrier 28, will leave the channels of the rails 10 and 11, and release the latter for free tilting movement on its bearings 27, which movement is directed by the rollers 29 following the curvature of the guide member 39, the forward or upper end of the support or carrier 28 taking a position inwardly of the opening in the top of the bin, when the material contents of the sack will be discharged from the open end thereof and into the bin. To prevent the sack *b* from leaving the carrier, during the dumping operation, a pair of hooks 40 are arranged on the lower end wall of the latter, and are adapted to have their bent pointed ends forced into the lower end portion of the sack, when the same is placed in position, and prior to the elevating operation of the carriage. To facilitate the tilting movement of the support or carrier 28 to and from dumping positions, a roller 41 is journaled transversely of the upper end of the rails 10 and 11, and directly at the ends of the lower faces thereof, so as to be contacted by the bottom wall of the support or carrier in its movements as stated. Upon the releasing of the pawl 38, and turning the hand crank 37 in a reversed direction, the cable 30 will be unwound from the winding roller 34, and the carriage will be returned to lowered position. The initial returning movement of the carriage will effect the tilting of the support of carrier 28 back to its normal position thereon, and its rollers 29 will be directed backwardly into the channels of the rails 10 and 11 by the guides 39.

For the purpose of supporting the track frame or rails 10 and 11 in permanently inclined operative elevating or hoisting position, a forwardly or oppositely inclined frame is provided and the same comprises a pair of spaced legs 42, one having its upper end connecting the rail 10 and the other the rail 11, as at 43, and a pair of horizontally spaced transversely extending bars 44, the lower ends of these legs 42 being provided with suitable rollers or casters 45 in rolling contact with the ground or floor level, substantially as shown in Fig. 1.

For the purpose of moving the apparatus or device from one operative position to another, the lower ends of the rails 10 and 11 are adapted to be raised from their normal contacting or supporting position on the floor or ground surface, so as to permit the rollers 26 to have free rolling contact with the latter, a foot lever 46 is pivotally mounted, as at 47, to a plate or support 48 which is clamped in position, by means

of suitable fastenings such as the U-bolts 49, on the vertical frame member or pipe section 15, of the elevating or hoisting carriage. The inner end portion 48', of the 5 foot lever 46, is rearwardly curved to provide a cam-like surface adapted to act on a roller 50 which is journaled, as at 51, to the under face of the rail 11, whereby when the pressure of the foot of the operator is exerted in a downward direction on the foot 10 engaging portion of the lever 46, the track frame or rails will be lifted from the ground or floor level and the weight of the apparatus or device will be borne directly on the 15 rollers 26, of the carriage, and correspondingly distributed on the rollers or casters 45 of the rear supporting frame legs 42. To retain the track frame or rails 10 and 11 thereof, in raised position throughout 20 the movement of the apparatus from one operative position to another, at the limit of the downward movement of the foot lever 46, a resilient latch device 52, which is secured in position on the plate or support 25 48, will engage over the foot portion of the lever, and will hold the same against retrograde movement under the weight of the track frame or rails, substantially as shown in Fig. 5. To lower the trackway or rails 30 10 and 11, and to release the carriage for operative movement thereon, the operator will release the latch member 52 from its engagement with the foot lever 46, and the trackway or rail frame will be lowered to 35 have its lower end again rest on the ground or floor level for the next hoisting and dumping operation of the apparatus or device.

From the foregoing, it will be readily apparent that the invention provides for an extremely simple and inexpensive construction of elevating and dumping device, and one which is capable of universal use, in stores and warehouses or on the farm 45 for the handling of all kinds of powdered, granular, or other forms of loose materials in bulk, or in packages, or articles of merchandise as the case may be, effectively dumping such materials in the bins provided 50 for the purpose, or to carry the same to the upper floors of a building or the like, and thus efficiently performing such function with a minimum cost in labor and time for its proper transportation from one point to 55 another and of its manipulation when in position.

Having fully described the invention, what is claimed is:—

1. In an apparatus of the class described, 60 a portable elevating trackway, an upright carriage movably mounted on said trackway, said carriage having its top extended outwardly with respect to said trackway to provide a carrier support, means for elevating and lowering said carriage on said

trackway, and a material carrier pivotally mounted at a point between the transverse center thereof and its lower end on the said carrier support whereby the upper end of the carrier will extend rearwardly and into 70 said trackway and releasable for tilting movement for the dumping of material therefrom at the limit of the upward movement of the carriage.

2. In an apparatus of the class described, 75 a portable elevating trackway, an upright carriage movably mounted on said trackway, said carriage having its top extended outwardly with respect to said trackway to provide a carrier support, means for elevating and lowering said carriage on said trackway, and a material carrier pivotally mounted at a point between the transverse center thereof and its lower end on the said carrier support whereby the upper end of 80 the carrier will extend rearwardly and into said trackway and releasable for tilting movement for the dumping of material therefrom at the limit of the upward movement of the carriage, and means projecting 85 from the upper end of said trackway for directing the tilting movement of said carrier.

3. In an apparatus of the class described, 90 a portable elevating trackway, an upright carriage movably mounted on said trackway, said carriage having its top extended outwardly with respect to said trackway to provide a carrier support, means for elevating and lowering said carriage on said 95 trackway, and a material carrier pivotally mounted at a point between the transverse center thereof and its lower end on the said carrier support whereby the upper end of the carrier will extend rearwardly and into 100 said trackway and releasable for tilting movement for the dumping of material therefrom at the limit of the upward movement of the carriage, and means projecting 105 from the upper end of said trackway for 110 limiting the upward movement of the carriage and for directing a tilting movement of the carrier.

4. In an apparatus of the class described, 115 a portable elevating trackway, a carriage mounted for rolling movement along said trackway and having an outwardly projecting end, means for hoisting and lowering said carriage on said trackway, means for limiting the upward movement of said carriage, a material carrier pivotally mounted eccentrically thereof on the upper end of said carriage and normally held in material supporting position, rollers carried by said carrier and arranged in engagement with said trackway for normally retaining the same in such material supporting position, said rollers being adapted to leave the trackway at the limit of the upward movement of said carriage to release said carrier for free 120 125 130

tilting movement on its pivotal connection with said carriage, and guides at the upper end of said trackway for directing the tilting movement of said carrier to material dumping position.

5. In an apparatus of the class described, a portable elevating trackway, a carriage mounted for rolling movement along said trackway, means for hoisting and lowering 10 said carriage on said trackway, means for limiting the upward movement of said carriage, a material carrier pivotally mounted on the upper end of said carriage and normally held in material supporting position, 15 rollers carried by said carrier and arranged in engagement with said trackway for normally retaining the same in such material supporting position, means at the lower end of the carrier for securing thereon a material filled sack in position with its open end upwardly thereof, said rollers being adapted to leave the trackway at the limit of the 20 upper movement of said carriage to release said carrier for free tilting movement on its 25 pivotal connection with said carriage, and guides at the upper end of said trackway for directing the tilting movement of said carrier for the dumping of the material from said sack.

30. 6. In an apparatus of the class described, a portable elevating or hoisting trackway comprising a pair of spaced rails, a carriage mounted for rolling movement along said rails, means for hoisting and lowering said 35 carriage on said trackway, a material carrier mounted on said carriage and releasable for tilting movement for the dumping of material therefrom at the limit of the upward movement thereof, means for supporting 40 said trackway in normally inclined hoisting position, rollers carried at the lower end of said carriage and by said supporting means, and means for raising said trackway with 45 respect to said carriage, whereby the weight of the apparatus is borne directly by the said rollers for the movement of the same from one operative position to another.

7. In an apparatus for the purpose set

forth, a portable elevating trackway, a carriage movably mounted on said trackway and having rollers at the lower end thereof, means for elevating and lowering said carriage on said trackway, a carrier pivotally mounted on the upper end of said carriage and releasable for tilting movement for 55 dumping at the limit of the upper movement of the carriage, and means on the carriage and engaging with the trackway for elevating the latter with respect to the carriage whereby the weight of the apparatus is carried directly by said rollers when moving the apparatus from one point to another. 60

8. In an apparatus for the purpose set forth, a portable elevating trackway, a carriage movably mounted on said trackway and having rollers at the lower end thereof, means for elevating and lowering said carriage on said trackway, a carrier pivotally mounted on the upper end of said carriage and releasable for tilting movement for 65 dumping at the limit of the upper movement of the carriage, and means on the carriage and engaging with the trackway for elevating the latter with respect to the carriage whereby the weight of the apparatus 70 is carried directly by said rollers when moving the apparatus from one point to another, and releasable means for retaining the trackway elevated with respect to the carriage. 75

9. In an apparatus for the purpose set forth, means to provide a trackway, a carriage movably mounted on the trackway and extending into said means, means for elevating and lowering the carriage on the 85 trackway, a carrier pivotally mounted on said carriage and releasable for tilting movement to dump at the limit of the upper movement of the carriage, and means projecting from the upper end of the trackway for limiting the upward movement of the carriage and for directing a tilting movement of the carrier. 90

In testimony whereof, I affix my signature hereto.

SAMUEL P. ERWIN.
